UNITED STATES PATENT OFFICE

JOHN F. ROBB, OF CLEVELAND HEIGHTS, OHIO, ASSIGNOR TO KOEHRING COMPANY, OF MILWAUKEE, WISCONSIN, A CORPORATION

TRUCK MIX METER FOR TILTABLE TRUCKS

Application filed May 2, 1930. Serial No. 449,300.

Object of invention:

What are commonly called truck mixers are being used today to transport concrete which has been previously mixed at a central mixing plant, to a place of deposit for use; such mixers are likewise used to transport aggregates of the concrete mix, in un-mixed condition, to the place of use; and mixers of this same general type are used to transport properly mixed aggregates of the batch, and the mixing element or drum is maintained in slow rotation to merely keep the materials properly agitated to prevent premature settlement or segregation thereof in transit.

My present invention embodies certain control mechanism suitable for such types of truck mixers wherein the mixing drum which under some conditions may be merely a transporting drum or a slow agitating drum, is tilted in order that it may be emptied of the batch of concrete aggregates at the proper site where the batch is to be emplaced. The said control instrumentalities involve a timing device designed to insure that the aggregates are retained by the mixing drum when the drum is employed as the preliminary mixing means and receives merely measured quantities of aggregates. The invention includes also a revolution counting counter, the function of which is to definitely indicate the number of revolutions which the drum has made in transit or even when the truck is stationary, this being desirable where specifications require a definite amount of rotation of the drum to obtain a mixture of proper integrity. The indicating counter for the revolutions of the drum is also advantageous where already mixed aggregates are within the drum and are being transported, so that the receiver will know that during the transporting movement of the truck the drum has been rotated a certain number of revolutions by which the contents thereof are kept properly agitated to prevent the segregation or settlement within the drum that would destroy the homogeneousness of the mix.

In the drawings—

Figure 1 is a side elevation of a mixing truck embodying the invention.

Figure 2 is a fragmentary side view showing more particularly the control mechanism alone.

Figure 3 is a fragmentary top plan view showing more clearly the connection between the water valve arm and the actuating slide therefor, including a vertical lever.

Figure 4 is a side elevational view of the parts of Figure 3.

Figure 5 is a fragmentary perspective view of the batchmeter setting shaft and gearing.

Figure 6 is a detail fragmentary view of the internal counter mechanism for the revolution counting operation.

Operation and construction of the invention

By describing the operation of my invention and referring to the various parts, the construction thereof will become readily apparent. It will first be noted that the truck mixer illustrated may be of any conventional type wherein is employed the main truck 1, the cab 2 for the driver, the wheels 3, the rear ones of which only are shown, an engine driven shaft or power device 4 suitably geared to be operated from the engine which propels the truck, and connected by the usual universal joint 5 with the rear section 4a leading to the differential at the rear axle of the vehicle.

A counter shaft 6 is arranged parallel with the engine shaft 4 which is connected by any suitable gearing with the counter shaft 6, the gearing being disposed in the casing 7. Upon the truck frame 1 is carried a mixing drum 8 which is pivoted at its rear end at 9 so that it may be tilted upwardly by the use of a hydraulic hoist 10 with suitable cable connections 11 leading to arms 12 projecting downwardly from the bottom of the drum frame 13 at its front end. The drum frame 13 directly supports the drum 8 and the pivot connection 9 is between the frame 1 and the drum frame 13.

The operation of elevating the front end of the drum 8 to discharge it is well known.

and simply consists in supplying the hydraulic pressure medium to the hoist 10.

My drum 8 is equipped at its front end with suitable bracket means 14 which carries a water tank 15. Now this water tank may not be used when my truck mixer is employed merely for transporting wet mixed aggregates, but I am illustrating the same in view of different adaptations and uses 10 to which the truck mixer may be put.

This brings me to the control instrumentalities which are the principal features of my invention.

It will be observed that I employ a drum 15 rotating shaft 16 adapted to be connected by a clutch 17 at its front end with a clutch 18 of a drive shaft 19 which is normally driven by sprocket and chain connection 20 leading to the shaft 6, which shaft it will 20 be remembered is driven from the engine shaft 4.

I utilize, suitably supported by the main truck frame 1 as by means of a vertical bracket 21, a timing device in the nature of 25 a batchmeter which is fully described in the Letters Patent of Trester, No. 1,532,277, dated April 7th, 1925. This batchmeter in the present construction is driven or operated by being geared to the drum drive 30 shaft 16 as by a sprocket chain 22, see Figure 2, instead of being driven directly from the mixing drum itself as shown in the Trester patent. I utilize for the purpose of clutching the drum rotating shaft 16 to 35 the engine driven shaft 19, a main control lever 23 adapted to be locked in adjusted positions by the usual latch means 24, and notch segment 25. If a water tank 15 is used on my machine I provide the arrangement 40 shown in Figures 2 and 4 to best advantage to establish an interlock between the water tank and the lever 23 so that the lever 23 may not be operated to cause rotation of the drum 8 for mixing until the water tank 45 has discharged its liquid contents into the mixing drum. With the above in mind, it will be observed that the tank 15 is yieldably supported by brackets 15' and 15" upon the 50 main bracket 14 at the front of the drum 8, a spring 26 being adapted to move the tank 15 upwards after the water in the tank has been discharged. As seen in Figure 1, the spring 26 is compressed because the tank 15 contains a supply of water for a mixing 55 operation. It will be seen that the lower bracket 15' has a control rod 27 extending laterally and downwardly with its lower end in the path of a lock lug 28 on the axis portion of the lever 23. The lever 23 is provided with an arm 29 which is connected with a slide 30, see Figure 4, working horizontally upon guide arms 31 of a bracket 32 projecting from a main bracket 33 on the truck frame 1. The purpose of the slide 60 30 is to engage the lower end of the valve

operating lever 34 which works the valve arm 35 to open and close the valve in the pipe 36 leading from the tank 15 in the mixing drum 8. This opening of the valve member is accomplished by the preliminary 70 movement of the lever 23 and until the water in the tank passes into the drum 8 ready to be mixed with the aggregates in the drum, the lever 23 cannot be moved downwards other than to that extent to cause the water 75 to be supplied to the drum 8 because the locking lug 28 will engage the rod 27. However, when the water has been emptied from the tank 15 into the drum 8, the spring 80 26 lifts the tank 15, disengaging the rod 27 from the lug 28 and rendering the lever 23 free to be further moved to now connect the drum 8 to be rotated from the engine driven shaft 19. By this last operation of the lever 23 to start the rotation of the 85 mixer 8, the timing device generally indicated at A is set into operation by means shortly to be described. The said secondary movement of the lever 23 causes its lug 23a intermediate its ends to engage and push 90 down on a plunger 37 which plunger rocks a bell crank lever 38 and causes the clutch member 17 to engage the clutch member 18. The mixing drum 8 is thus started into rotation and at the same time as this action 95 is performed, the downward movement of the plunger 37 carries down with it the L-shaped actuating slide 39, see Figure 2, and Figure 5. The setting of the timing device A into operation is done in substantially the same manner as presented in the Trester patent above identified, the slide 39 having teeth 40 meshed with a one-way actuated pinion 41, see Figure 5, which pinion is loose on a shaft 42 having a driven 100 pinion 43 meshing with the teeth of a slide 44 which connects with the setting rod 45 of the timing device or batchmeter A. In this way when the L-shaped slide 39 is carried down, the shaft 42 is turned and raises the 105 slide 44 and the rod 45 and sets the batchmeter into action.

Now it must be understood that there must be some locking control to prevent the operation of the hydraulic hoist 10 to tilt and discharge the mixing drum 8, when the said drum 8 is performing its complete mixing cycle or period of operation, necessary to insure a proper mixing of the aggregates. Thus I provide under the control of the batchmeter A and particularly its setting rod 45 a lock member 46 which engages the valve lever 47 that controls the admission of the pressure medium to the cylinder of the hoist 10 for actuating the cable 11 to raise 110 and tilt the mixer 8. So long as the batchmeter is operating after having been set into action, the valve lever 47 is locked so that operator cannot cause a tilting discharge of the mixer. When the batchmeter finishes its 115 120 125 130

control cycle of operation, as presented in the Trester patent, the setting rod 45 moves downwardly by a release action and thereupon releases the valve lever 47 so that it 5 may be operated by the truck man to discharge the mixer 8.

It also should be observed in Fig. 5 that the pinion 43 is freely rotatable on the shaft 42 and is provided with a one-way acting dog 10 clutch face 43^a. Splined to the shaft 42 and movable into and out of engagement with the clutch face 43^a of the pinion 43 is a clutch member 43^b which when in the position shown establishes driving relation between 15 the shaft 42 and the pinion 43. A bell crank clutch shifter yoke 43^c engages the clutch 43^b, said yoke being pivotally supported on the standard 43^d.

The long arm of the clutch shifter yoke 20 43^c has an offset portion 43^e and finally terminates in the resilient blade portion 43^f lying in the path of the two pins 44' projecting from the rack bar 44. A snap-over spring 43^g connects the offset portion 43^e of 25 the shifter yoke at one end and extends across the yoke pivot at one side thereof, connecting with the arm 43^h projecting laterally from the standard 43^d. The lower pin 44' on the rack bar 44 engages the blade portion of 30 the shifter yoke just after the rack bar 44 is raised by the downward movement of the rack 39 incident to the setting of the batchmeter, and as the batchmeter is set the shifter yoke is moved to disengage the clutch members 35 43^a and 43^b to free the pinion 43 from operative connection with the shaft 42. As the axis of the spring 43^g passes the pivotal center of the shifter yoke 43^c, the spring assists in shifting the yoke and also holds the 40 clutch when shifted in its respective positions.

Since the clutch is thrown out incident to the setting of the batchmeter, the rack bar 44 is now free to drop down incident to the 45 release of the batchmeter at the end of the predetermined mixing period, as governed thereby. When this release takes place, the parts again shift to the position as shown in Fig. 1 which, due to the dropping of the 50 latch bar, causes the clutch shifter yoke to be again moved to clutch engaging position to be subsequently actuated incident to movement of the rack bar 39.

The previous downward movement of the 55 slide 39 caused a turning of the shaft 42 because the ratchet devices 48 and 49 were operative to transmit movement at that time from the slide 39 to the shaft 42, which shaft carries the ratchet member 48 fixed thereto.

60 When the lever 23 is released by controlling its latch 24, the spring 50 will force the plunger 37 upwards and disconnect the clutch members 17 and 18 in a self-evident manner. The slide 30 is so interlocked with

65 of one from the other is obtained, but when the mixer 8 is rocked to tilt it, the lever 33 is adapted to separate from the slide 30, later reengaging said slide as seen in Figure 4 when the mixer moves back to its horizontal position. In like manner the rod 27 70 is adapted to separate and move back to its original position of Figure 2 relatively to the lever 23.

In conjunction with my timing batchmeter A, I utilize a batch counting register and indicator 51 which is operated in substantially the manner of the Trester patent previously referred to, and also a new revolution counter 52, a detail of which is seen best in Figure 6. The purpose of the revolution counter 52 is to enable a person who has received concrete delivered by the truck mixer to determine when the concrete arrives how many revolutions have been performed by the drum 8. This information is of importance both to the receiver of the aggregates being delivered and to inspection service where government, state, or other inspection is maintained. The counter 52 is 80 operated to count the revolutions by a gearing including shafts 53, 54, and 55 with intermediate bevel gears leading to and connecting with the operating shaft 56 of the batchmeter. The gear ratios of the gearing just mentioned will be such that the indicator or register 52 will be operated to properly count the number of times the mixer 8 rotates, the said gear ratios involving of course the said gears just mentioned and the 85 sizes of the gears which drive the shaft 56 from the shaft 57 which is operated by the sprocket chain means 22 previously referred to. Obviously, when the number of revolutions of the drum 8, for each batch, are 90 counted upon the indicator or register 52, the dumping of the batch of mixed aggregates from the drum 8 should enable a 95 restoration of the counting wheels of the counter 52, to zero. For this purpose, every 100 time the valve lever 47 is operated to actuate the hoist 10 and discharge the drum 8, a rod 58 connecting said lever to the normalizing shaft of the counting wheels of the register 52 will cause zeroizing action of said shaft 105 upon the said wheels. Of course it will be understood that the levers 23 and 47 may, if desired, extend into the cab 2 so as to be 110 convenient to the operator of the machine sitting in the cab, or rods may lead from the cab to set these levers, enabling them to be operated from the cab, as well as directly from his position alongside the machine.

Having thus described my invention, what I claim as new and desire to secure by Letters Patent of the United States, is—

1. In control mechanism for truck mixers, in combination, a truck, a mixing drum thereon adapted to be tilted to discharge, a hoist connected with the drum to discharge 130

the same, a power shaft, a device for connecting the power shaft with the drum to rotate it, and lock means for the hoist controlled from the above mentioned device 5 so that the hoist may not be operated until said device has been actuated.

2. In control mechanism for truck mixers, in combination, a truck, a mixing drum thereon adapted to be tilted to discharge, a 10 hoist connected with the drum to discharge the same, a power shaft, a device for connecting the power shaft with the drum to rotate it, and lock means for the hoist controlled from the above mentioned device so 15 that the hoist may not be operated until said device has been actuated, including a timing device requiring a certain number of rotations of the drum to be performed before the hoisting device is released from 20 its lock device.

3. In control mechanism for truck mixers, in combination, a truck, a mixing drum thereon adapted to be tilted to discharge, a hoist connected with the drum to discharge 25 the same, a power shaft, a device for connecting the power shaft with the drum to rotate it, and lock means for the hoist controlled from the above mentioned device so 30 that the hoist may not be operated until said device has been actuated, including a timing device requiring a certain number of rotations of the drum to be performed before the hoisting device is released from 35 its lock device, and a revolution counter included in said timing device to indicate the number of revolutions that have been performed by the drum.

4. In control mechanism for truck mixers, in combination, a truck, a mixing drum 40 thereon adapted to be tilted to discharge, a hoist connected with the drum to discharge the same, a power shaft, a device for connecting the power shaft with the drum to rotate it, lock means for the hoist controlled 45 from the above mentioned device so that the hoist may not be operated until said device has been actuated, including a timing device requiring a certain number of rotations of the drum to be performed before the hoisting 50 device is released from its lock device, a revolution counter included in said timing device to indicate the number of revolutions that have been performed by the drum, and means to restore the said counter to zero operated incident to the operation of 55 the hoisting means.

5. In control mechanism for truck mixers, in combination, a truck, a mixing drum thereon adapted to be tilted to discharge, a 60 hoist connected with the drum to discharge the same, a power shaft, a device for connecting the power shaft with the drum to rotate it, lock means for the hoist controlled from the above mentioned device so that the 65 hoist may not be operated until said device

has been actuated, including a timing device requiring a certain number of rotations of the drum to be performed before the hoisting device is released from its lock device, a revolution counter included in said timing device to indicate the number of revolutions that have been performed by the drum, and means to restore the said counter to zero operated incident to the operation of the hoisting means, and said timing device including a register for adding consecutive registrations of the operations of the hoisting device. 70

6. In control mechanism for truck mixers, in combination, a truck, a mixing drum rotatably mounted thereon, power means on the truck, driving means to drivingly connect the power means with the drum to rotate it, means for tilting the drum to discharge it, and means for locking the said 80 tilting means against use prior to the operation of the means employed to drivingly connect the power means with the rotating means whereby rotation of the drum is compelled before discharging by tilting thereof 85 is performed. 90

7. In a control mechanism for truck mixers, in combination, a truck, a mixing drum thereon, hoist means for tilting the drum to discharge the same, instrumentalities for operating the hoist, a water tank associated with the drum and movable therewith upon tilting of the latter, lock means for the hoist, operating instrumentalities to prevent operation of the latter until the drum has been rotated a predetermined number of rotations, a device for causing rotation of the drum, a control therefor, and means associated with the water tank for preventing operation of the drum rotating control means until the contents of said tank have been 100 emptied into the drum. 105

8. Means as set forth in claim 7, in which the last mentioned means involves connections between the water tank mechanism and the drum rotating instrumentalities which connections are formed so as to separate when the drum is moved upon the truck for discharging operation. 110

9. In control mechanism for truck mixers, in combination, a truck, a mixing drum tiltably mounted thereon, rotating means for the drum, a power source, means to connect the rotating means with the power source to render the former operative, a timing device for compelling a certain number of rotations of the drum before it can be discharged, means for causing discharge of the drum, and means for setting the timing device into operation initiated by the actuation of the means which connects the drum rotating means with the power source. 115 120

10. A machine as set forth in claim 9, combined with water tank means for supplying water to the drum and in which the dis- 125 130

charging means comprises a hoist to tilt the drum, and an interlock between the water supply means and the instrumentality for causing rotation of the drum from the power source for preventing said rotation until the water supply means has supplied a proper charge of water to the drum.

11. In control mechanism for truck mixers, in combination, a truck, a mixing drum mounted thereon, a hoist connected with the drum to rock the same to discharge it, a power source on the truck drum rotating means; clutch means for connecting the drum rotating means with the power source, including an operating lever and a timing device for compelling a certain number of rotations of the drum set to operation by actuation of said lever to render the clutch means operative, and means for operating said hoist controlled by said timing device so that the hoist cannot be actuated until after the drum rotating means has been in operation a certain length of time.

12. A machine substantially as set forth in claim 11, combined with water supply means for the drum and connections between the water supply means and said lever to control the operation of the lever and prevent the clutch means from being rendered active until water has been supplied to the drum for mixture with the aggregates therein.

13. In control mechanism for truck mixers, in combination, a truck, a mixing drum thereon, a power source, drum rotating means, clutch means to connect the drum rotating means with the power source, an operating device for said clutch means, a water tank associated with the drum to supply water thereto, an interlock between the water tank means and said operating device whereby the operating device cannot be operated to cause rotation of the drum until the water supply tank has been controlled to supply water to the drum, and means for opening and closing the supply of water to the drum from the tank under the control of said operating device.

In testimony whereof I affix my signature.

JOHN F. ROBB.
